Application October 3, 1947, Serial No. 777,817
 In Great Britain October 3, 1946

9 Claims. (Cl. 315—323)

1

This invention relates to electronic devices using multigap cold cathode gaseous discharge tubes.

The object of the invention is to record information concerning the pulses of a train of electric pulses and deliver up that information, when required, in a number of alternative forms.

According to one of its features, the invention consists of an electronic device which comprises a cold cathode gaseous discharge tube having a number of gaps adapted to fire in a predetermined order on the application to the said gaps of consecutive pulses of electrical energy due to the influence of a fired gap on the potential required to fire an adjacent unfired gap, means for applying in turn to the said tube a first group of pulses and a second group of pulses and means for giving a signal dependent on the firing of a predetermined gap during the application of the second group of pulses.

The nature of the invention will be more readily appreciated from a description of certain embodiments illustrated in the accompanying drawings, in which:

Fig. 1 is a circuit diagram of a device adapted to record a number of pulses and subsequently deliver a signal or signals depending on that number;

Fig. 2 is a circuit diagram of a device adapted to record a number of pulses and then continuously deliver information characteristic of that number in the form of a delay or phase position in relation to a recurrent cycle of pulses.

Both these embodiments make use of tubes of the type described in my application, Serial No. 763,655, filed July 25, 1947, now abandoned, and in my joint application with C. H. Hough, Serial No. 763,656, filed July 25, 1947, of which a brief description will now be given.

In these specifications there are described cold cathode gaseous discharge tubes having a number of discharge gaps which fire in succession in a predetermined order, on application of pulses to the said gaps in common, due to ionisation of an unfired gap, caused by the discharge in an adjoining fired gap.

A first pulse applied to the tube will fire only a predetermined gap, called the starting gap, and various alternative measures to ensure this include the closer spacing of the electrodes of the starting gap in comparison with the other gaps, a bias potential applied to the starting gap only, or the provision of a permanently discharging gap, called a pilot gap, adjoining the starting gap, causing this gap to be permanently ionised.

2

After a sequence of discharges of the gaps of the tube, and when the last gap (in the predetermined order) has fired, all discharges are extinguished and the tube is allowed to deionise before the commencement of another firing cycle. If it is required to operate such a tube from a continuous sequence of regularly spaced pulses, as in the case of the embodiment illustrated in Fig. 2, a limit is set to the permissible frequency of pulse repetition by the need for a time interval between pulses, long enough to allow the gaps to become deionised (except the starting gap when a pilot gap is provided as previously described).

15 If gaps (except as aforesaid) remained ionised, there would be no guarantee that the starting gap would fire first, in preference to the others, in a second or subsequent cycle of pulses nor that the predetermined firing order would be maintained.

20 To enable higher pulse rates to be used, measures to reduce deionising time may be taken, for instance, by the use of special gas atmospheres in the tube. Alternatively it may be arranged

25 to ensure that one or more pulses succeeding that which fires the last gap, are prevented from firing any gaps in the tube so that a time longer than the interpulse interval is allowed for deionisation of the gas in the gaps. Methods of doing this are described in my application Serial No. 777,815, filed October 3, 1947, where (inter alia) the reduction of the inter-electrode voltage, so that pulses do not reach the level necessary to cause firing, for the duration of such one or more pulses, or the use of two or more tubes operating alternately, are outlined.

30 It is possible to apply a constant inter-electrode potential to the gaps of the tube, insufficient by itself to initiate a discharge in the gaps but sufficient to maintain a discharge, once initiated. With such a potential applied, gaps once fired, will continue to discharge and at the end of a cycle, all will be discharging and must be extinguished before the next operation cycle of the tube. There are various ways of doing this, one of which is used in the embodiments of the invention to be described.

35 If no such discharge-maintaining potential is applied, discharges will collapse between pulses, during the firing cycle of the tube and the interval between pulses must not be so long that the ionisation can fall below the level necessary to secure sequential firing.

40 This involves the use of pulse rates such that the tube has not time to become deionised be-

tween consecutive pulses at the end of the firing cycle after extinguishment of the discharges, and measures such as those described in application, Serial No. 777,815, filed October 3, 1947, become essential.

In my joint application with C. H. Hough, Serial No. 763,656, filed July 25, 1947, a phenomenon occurring in multi-gap tubes of this type, and called the "memory effect," is described.

This effect consists of a rise in the voltage required to fire a gap, which follows an extinguished discharge in that gap, when certain electrode materials and gases are used in the construction thereof.

If tubes possessing this feature, are supplied with pulses to their gaps, in common, and with no constant discharge-maintaining potential, a gap once fired will ionise the adjacent unfired gap and extinguish at the end of the pulse which fired it. The next pulse will fire the ionised adjacent unfired gap but will not refire the extinguished gap (owing to the said rise in its critical firing voltage), it being arranged that the pulse amplitude is below such critical voltage.

This "memory effect" persists long enough to ensure that gaps once fired, will not again fire during the firing cycle of the tube, but when all gaps have fired and all possess the "memory effect," the first gap to recover will be that which has been extinguished for the longest time, i.e. the starting gap, and this alone will fire on the first pulse of the next cycle. A corresponding decay of the memory effect will pass down the gaps of the tube in the predetermined firing order, in advance of the firing sequence, so that all in turn are ready to fire from successive pulses.

A small bias may be applied to the starting gap to make quite sure that the sequence starts with that gap in cycles after the first, but this bias must not be large enough to leave the starting gap permanently discharging. It is also an advantage to insert a relatively large resistance load in series with one of the common pulse feed connections to the gaps, so that immediately on the firing of one gap, the increased voltage drop in the resistance makes it impossible for another gap to fire from the same pulse. This enables the tube to be worked at a lower level of discrimination due to memory effect between gaps and still secure the correct firing order.

If, in the case of a tube with a maintaining battery and without the memory effect, there is a break in the pulse train applied to the tube so that it is left with a certain number of gaps discharging, this condition will persist for an indefinite time and on the application of pulses being resumed the tube will continue to discharge in sequence starting at the next unfired gap following the last gap to be fired at the time of the break. The standing potential of the maintaining battery must be adjusted so that there is no risk of ionisation spreading so as to prime more than the one adjoining gap, lest the first pulse after the break should fire more than one gap.

If there is no maintaining battery or if a tube is used having the memory effect, it is necessary to prolong the last pulse, preferably at reduced amplitude, to minimise the risk referred to in the last paragraph, or to apply a holding potential during the break period. Where, however, the break does not exceed the deionising time

of the tube, such precautions and measures are unnecessary.

It is obvious, of course, that if the last gap is reached by the last pulse before the break, the tube must be allowed to be extinguished so that it recovers its quiescent state ready to commence a new firing cycle on the resumption of pulsing and the means provided for extinguishing the tube in its normal cycle, must over-ride any discharge-maintaining means used for the purposes outlined in the last two paragraphs.

Fig. 1 illustrates a device incorporating a tube of the type described and the upper half of the drawing depicts a tube of the non-memory type having ten discharge gaps.

This device is designed to have a number of gaps fired by signal pulses, after which a system of relays causes a master pulse train to be applied to the tube, firing the remaining gaps of the tube until, on reaching the last gap, the tube is extinguished and the master pulse disconnected. Means are provided for producing an impulse for every master pulse so applied to the tube, and the number of these impulses is, of course, the complement of the number of signal pulses to the total number of gaps of the tube.

This information may be delivered up immediately or stored and delivered later, by breaking the connection to the master pulse source and only connecting it when the information is required.

The tube 1 has a common anode 2 and cathodes 3 and 4, cathode 3 having nine projections like the teeth of a comb, towards the anode, defining nine gaps 5, 6, 7, 8, 9, 10, 11, 12 and 13 between 3 and 2, and cathode 4 having a surface of a larger area than the other cathode points, defining a tenth gap 14 between 2 and 4.

Gap 5, the starting gap, is shorter than the others to ensure that a first pulse will fire that gap in preference to the others when the tube is deionised. The gaps 6 to 14 are all of the same length and are such that a pulse will only fire them when the gas within them is ionised by a discharge in an adjoining gap. The anode, through a resistance 16, cathode 3, through a resistance 17, and cathode 4, through a resistance 18, are connected to a battery 20 (representing any convenient source of constant potential) and the potential of this battery is such that it cannot by itself initiate any discharge, but is sufficient, by itself, to maintain a discharge, once initiated.

Pulses are applied to the gaps of the tube through a feed condenser 19.

When, in a sequence of discharges in the tube, gap 14 is fired, a condenser 23, connected across anode 2 and cathode 4, and normally charged to a potential somewhat higher than that of battery 20 in a manner to be described, is discharged across gap 14, and lowers the inter-electrode potential across all gaps to a value below that required to maintain a discharge, whereupon the discharges are extinguished.

This extinguishment surge is assisted by the use of a relatively high resistance for 16, the larger area of cathode 4 passing a higher current in gap 14 than the other gaps and causing a sharp voltage drop across 16.

The area of 4 cannot be indefinitely extended, however, or the general level of ionisation of the tube be increased to such an extent by the increased current passing in gap 14 that the critical firing voltage of the gaps is lowered to a point enabling them to refire during the same pulse as

that which fires 14, even on the lower voltage produced by the discharge of condenser 23 and the voltage drop in 16.

Generally speaking, the larger the number of gaps in the tube, the larger the current surge required from the last gap to produce the extinguishing voltage drop and so a limit to the area of 4 is a limit to the number of gaps which can be extinguished in this way. When this limit is reached, for any design of tube and pulse rate, other methods of extinguishment may be resorted to, such as an external switching circuit or quenching pulse generator, triggered by the discharge current of the last gap, to switch off or oppose the battery 20. In Fig. 2, contacts b4 and d4 switch off the battery momentarily and similar relay arrangements could be incorporated in the circuit of Fig. 1 for the same purpose. Connections 24 and 25 are taken from the pulse input points of the tube, to the signal pulse generator 26 which contains a battery 27 and pulsing contacts IP. Signal pulse generator 26 is intended as a symbol of a pulse generator, such as might be used in connection with the device, and might be a key sender or dial in a telephone system, for instance, arranged for "make" impulsion.

Master pulse generator 28 is connected via transformer 29, in one leg, to 24 and 25 through contacts d1, d2, normally open.

Relay A is connected in series with one connection between 26 and 24 and 25.

When contacts IP are closed, on the first pulse of a train of signal pulses, one pulse is passed to the tube which adds to the potential across the electrodes from source 20, firing the starting gap. This pulse also adds to the potential across the condenser 23 causing this potential to become larger than that of the source 20.

Relay A operates, operating B over a1 front contacts. B operates C, over b1 front contacts, and C holds over c2 front contacts, c1 back contacts. Contacts c1 also prepare an operating path for D, on the release of B. Subsequent operation of IP contacts fire successive gaps of the tube 1 and A impulses in time with IP.

B, being slow to release, holds during the impulsion of IP and A, over a1 and releases at the termination of the signal pulses after the expiration of its release lag.

Contacts IP are now open and 26 is thus disconnected from the tube.

The release of B operates D over c1 front contacts, b1 back contacts and d1, d2, front contacts, connect master pulse generator 28, to the tube, the pulses therefrom firing the remaining unfired gaps of the tube and recording an impulse at terminals 38, from transformer 29, for each pulse.

When the last gap is fired, relay E operates from the discharge current through gap 14, being connected in the battery negative connection to the cathode of that gap only.

Relay E, operating, breaks the holding circuit of C at c1. C releases, releasing D at c1, disconnecting 28 from tube 1 at d1, d2, open. All relays and contacts are now as shown in the figure, and the device is ready to accept a new train of signal impulses.

As shown in Fig. 1, the stored information is automatically delivered up immediately after the termination of the signal pulses. It may be required to hold the information for later delivery. To achieve this, it is only necessary to break the circuit between master pulse generator 28 and 75 is applied to the tube, not immediately, but at

contacts d1, d2, for instance, with a switch or relay contacts, normally open.

After the termination of signal pulses, the device would then remain indefinitely with a certain number of tube gaps discharging, with relays A and B released, relays C and D operated and contacts d1, d2, closed ready for the switching-in of the master pulse on closing of the said switch or relay contacts. There is sometimes difficulty in securing a sufficiently stable inter-electrode voltage in the tube owing to the varying currents drawn as different numbers of gaps are discharging from time to time. Accordingly it is advisable to insert choke 21 and rectifier 22 connected between the anode and a tapping on the battery 20. The tapping is chosen so that the rectifier 22 is just non-conducting when all gaps are firing, that is to say, when the voltage drop across resistance 16 is at its maximum.

20 The precautions previously mentioned, to ensure that ionisation does not spread to more than one gap adjoining the last fired gap, should be borne in mind and, where there is no maintaining battery, or in the case of a tube with the 25 memory effect, measures must be adapted to prolong the discharges or discharge during the interval between the end of the signal pulses and the application of the master pulse.

This device represents the simplest application 30 of the invention. The functions of the relays could readily be carried out by electronic devices, for instance, the function of relays A and B could be entrusted to a time constant circuit upon the recovery of which, at the end of the signal pulses, 35 an electronic "flip-flop" circuit could be utilised to connect in the master pulses to the tube, the "flip-flop" being restored to its original state by a pulse generated by the discharge of the last gap of the tube.

40 The "flip-flop" circuit could be of known type and Fig. 2 shows such a circuit consisting of tubes 36, 37 and 38 and their connecting circuits.

It is frequently required that a recording device shall deliver information characteristic of 45 the applied signal pulses in continuous form, and Fig. 2 illustrates such a device where the delivered information continuously defines a time position or phase relationship in or to a continuing sequence of master pulses.

50 In Fig. 2 a cold cathode discharge tube 1 is shown, which closely resembles tube 1 of Fig. 1 and the circuits immediately connected with the operation of the tube are also similar, the same numerical references being used in the two figures for 55 corresponding items. The differences in the two tube circuits are confined to the pulse feed circuit to the tube and the components in the circuit exclusive to cathode 4.

In Figure 2, the circuit of cathode 4 includes 60 a resistance 31 and a transformer 32. The former is connected to a source of audio frequency signal, and voltages developed across 31 affect the precise time of firing of gap 14, so that output pulses from transformer 32, passing through a rectifier 33 which passes only the leading edges 65 of the pulses, and battery 34 which biases rectifier 33 suitably, are recovered from terminals 35, modulated in time by the audio frequency signals.

70 The operation of the device, in broad terms, is as follows:

Pulses are applied to the tube to fire a number of its gaps.

At the end of these impulses, a master pulse

at a certain phase in such master pulses which may be regarded as divided into successive cycles each having a number of pulses equal to the number of pulses in the operating cycle of the tube. A pulse at a certain phase in such cycle of pulses is regarded as the "zero" pulse of the cycles and may be marked or accentuated in some way or, alternatively, a separate zero pulse generator may be used, producing a pulse only at zero phase of the master pulse cycles.

The first zero pulse after the termination of the signal impulses, is applied to the tube which fires at another of its gaps from the zero pulse and continues to fire other gaps from the master pulses, giving an output pulse from terminal 35 on the firing of gap 14, after which the discharges in the tube are extinguished. The next master pulse after extinguishment starts a new firing cycle of the gaps of the tube which continues to fire in repeated cycles, indefinitely, till the master pulse is disconnected.

The firing of gap 14 takes place repeatedly at a definite phase position in the master pulse cycles in relation to the zero pulse, and this phase position depends upon the number of signal impulses originally applied to the tube.

The detailed operation of the circuits illustrated is as follows:

A source 64 of impulses and audio frequency signals is shown in the form of the microphone and dial circuits of a conventional telephone subset, though the invention is by no means confined to telephone systems.

The components shown are dial impulse contacts IP, "off-normal" springs ON, switch-hook or cradle contacts SH and microphone 59. Induction and anti-sidetone coils are omitted to simplify the drawing.

Wires 62 and 63 connect the subset to the device and are connected via leads 60 and 61 and condensers 57 and 58 to the ends of resistance 34 for the application of the microphone audio frequency output to gap 14 of the tube. Wires 62 and 63 also pass through two windings of a relay A, terminating on one side in a battery-earth connection and on the other side, in an earth connection.

On lifting the receiver, SH closes the loop at the subset end, operating A, through earth, battery, top winding of A, wire 62, IP, 59, SH, bottom winding of A, earth. A, operating, operates B on *a1* front contacts.

On commencement of dialling, ON front springs short-circuit microphone 59 and on the return of the dial, each dial impulse takes the form of opening IP, A releasing for each impulse.

B, being slow to release, holds during the impulsion of *a1* contacts. Meanwhile, *a2* contacts apply positive impulses from battery 63 through pulse input condenser 19, to tube 1, via *d6* back (or *c4* front contacts), *b5* front contacts, *a2* back contacts, the latter contacts closing every time A releases on the opening of IP.

On every impulse of IP one gap of tube 1 is fired.

The operation of the other relays is as follows: B, operating, operates C, on the first release of A after moving the dial, over *d2* back, *b2* front contacts, *a1* back contacts.

C, being slow to release, holds over *c2*, *b2*, *a1* (impulsing).

C, operating, operates D, over *c1*, and *d2* is opened, leaving *c2* to complete the holding circuit for C and *c4* to complete the pulse circuit for tube 1, in lieu of *d6*.

D holds over *d1*, *b1*, both front contacts.

At the end of dialling, B holds over *a1* front contacts, since A remains operated over the loop through IP, closed, 59, and SH, closed.

C releases, however, after its release lag, being open-circuited at *a1* front contacts.

On C releasing, the pulse feed circuit of tube 1, from 63, is broken at *a2* open and *c4* open, *d6* being also open since D remains operated.

10 The operation of the "flip-flop" circuit on the right in Fig. 2, will now be described.

A pentode 36 is normally biased positive on its suppressor grid by potential divider 41, 42, a connection from its anode being taken through feed condenser 39 to the pulse input of tube 1.

Valve 36 is also normally cut off on its control grid which is connected to the grid of one valve 37 of the "flip-flop" circuit having two valves 37 and 38.

20 The anodes of 37 and 38 are supplied with high tension current through anode loads 45 and 46 respectively, the anode of valve 37 being connected to the grid of valve 38 through resistance 49 and the anode of valve 38 being connected to the 25 grids of valves 36 and 37 through resistance 47.

Valves 37 and 38 are given a standing grid bias by battery 51, through resistances 48 and 50 respectively.

This is a conventional "flip-flop" circuit with 30 two stable conditions, one with one valve conducting and the other cut off, and the other, vice-versa.

Normally, 38 is conducting and its anode applies negative potential to the grid of 37 holding it and also 36 in the non-conducting state.

When, at the beginning of dialling, C and D are both operated, *c3* is open, and *d5* closed, *c3* opening before *d5* closes, since C operates before D.

When B releases at the end of dialling, C releases, closing *c3* and completing a path through *c3* and *d5*, to the grid of 38, from zero pulse generator 56. Zero pulse generator 56 emits negative pulses at zero phase of master pulse generator 57, and the first zero pulse after the release of C, at the end of dialling, cuts off 38 from the anode of which the control grids of 36 and 37 receive a positive bias due to the rise in anode voltage on cessation of anode current through 46, and 37 becomes conducting, whilst the control 50 grid of 36 is "opened."

Master pulse generator 57 is permanently connected to the suppressor grid of 36, through feed condenser 52, and when the zero pulse causes the "flip-flop" to change over and 38 control grid becomes "open," the anode potential of 36 falls negative (which does not affect tube 1) and the next master pulse after the zero pulse, cuts off the suppressor grid of 36, causing a positive pulse to appear on tube 1 via condensers 39 and 19. Successive master pulses continue to cause positive pulses to be applied to tube 1, firing its gaps in succession in repeated cycles, as previously described.

There is a possibility of the initial negative 65 pulse, when 36 becomes conducting, extinguishing the discharges in tube 1, and this may be prevented by inserting a rectifier (not shown) in the connection between condenser 39 and tube 1. Actually, the negative pulse will not usually occur 70 until the end of the zero pulse since it will generally be arranged that 57 will emit a master pulse at the same time as the zero pulse, cutting off 36 on its suppressor grid when the control grid of 36 is opened, but the negative pulse must come 75 sooner or later, when both pulses are absent.

It can be arranged, however, that the extinguishment of tube 1 will not affect its operation, since all the previously fired gaps and the next adjoining unfired gap will have enough residual ionisation for all to fire simultaneously, the previously fired gaps re-firing and the next unfired gap firing as it would have done without the extinguishment, when the next master pulse arrives.

As tube 1 completes successive firing cycles in response to the continuing master pulses, a pulse is passed to terminals 35 at the required phase position in relation to zero phase of the master pulse cycles and the precise firing time of gap 14 and of the pulse from 35 will be varied according to the instantaneous potential across 31 which is varied by the audio frequency signals from microphone 59.

There has thus been secured a succession of time modulated pulses at a phase in the master pulse cycles determined by the number of impulses dialled from subset 64, and this pulse may be applied to a distributor in those telecommunication systems where individual substations are allotted to, or communication channels are represented by, time positions in a cycle of pulses.

When the call terminates, SH contacts are opened, A releases, releasing B at *a1* back contacts, D releasing in turn at *b1* open, B, releasing before D, closes a circuit at *d3* front contacts, *b3* back contacts, connecting a battery 53 to the grid of 31 through condenser 54, applying a momentary negative pulse to 37, cutting off 37 and 36 on its control grid, and restoring the "flip-flop" to its other stable state. This circuit is later cut, on the release of D, after its release lag.

The zero pulse generator path to 38 grid is now broken at *d5*.

The tube 1 is protected from false impulses from 63 during this process since, on the release of A, when *a2* closes, with *b5* still closed, the circuit from battery 63 is broken at *d6*, *c4* being also opened when C released at the end of dialling. Contacts *b5* open after the release lag of B and *d6* cannot close until the release lag of D has expired after its release at *b1*.

At the end of the call, in the interval between the release of B and the release of D, that is to say during the release lag of D, the negative battery load to tube 1 is momentarily disconnected at *d4* so that the tube is extinguished. This is necessary because at the termination of a call the tube will usually be left discharging on some of its gaps, there being no further pulses to extend the firing cycle to the end of the array of gaps and cause the normal extinguishment measures to operate.

The circuit is now as drawn and is ready to accept new dial signals.

The functions performed by the relays could equally well be performed by corresponding electronic devices, for instance several "flip-flop" circuits of the type described could readily be made to do the same tasks. Where operating speeds are within the capacity of relays, however, it will frequently be advantageous to use relays to avoid added tubes and their power supplies.

Th device shown in Fig. 2 is capable of accepting a single train of pulses only and, with the simple subset shown, would only deal with single digit impulse trains.

This particular arrangement is only intended as an example to illustrate the nature of this embodiment of the invention. For use in larger systems, it is envisaged that signal impulse trains of considerably more than ten, will be used, in

combination with gas tubes having a correspondingly large number of gaps.

Alternatively, successive stages of selection may be introduced into a system responsive to successive digits in a decimal numbering system, though here, the simple system of impulsing described would need modification to the extent of passing digits after the first to the modulating part of the circuit and outward from terminals 35 whence, after demodulation, they could be used to provide signal impulses for a similar device responsible for secondary selection.

If a device of the type shown in Fig. 2 is used in a telecommunication system, though it is of course by no means confined to such application, it can be connected directly to the termination of an incoming distribution line and one such device will be required for every such incoming line.

There are systems where a limited number of interconnecting links are available to a larger number of incoming lines and when a device of the line finder type is used to connect a free interconnecting link to a calling line, a system of this type where individual lines are allotted to individual time positions in a repeated cycle of pulses, is described in the application of David Ransom et al., Serial No. 794,724, filed December 30, 1947.

In a system of this type a line finding device searches for and locks to the time position of a calling line and pulses at that time position, modulated by designation or other signals from the calling line, are demodulated before being passed to selecting apparatus responsive to designation signals, adapted to select a time position allotted to another line incoming to the system to which connection is required.

The device illustrated in Fig. 2 could readily perform this selection process by the application of demodulated signalling impulses to lines 62 and 63 in place of subset 64, the master pulse generator and zero pulse generator being synchronised with the distributor or other means entrusted with the transfer of the incoming lines to the various time positions to which they are allotted in the cycle of pulses.

According to the number of such signal impulses, therefore, so will the timing of the pulses emerging from terminals 35 coincide with the time position allotted to one or other of the other lines incoming to the system. These timed pulses may be applied to the same distributor as that which originally distributed the incoming lines into the time cycle or to a separate outgoing distributor, as is used in the said application last referred.

The embodiments shown in Figs. 1 and 2 make use of a tube without the memory effect and in which extinguishment of discharges at the end of a firing cycle is entrusted to condenser 23. Other methods of extinguishment may be used, however, such as a direct disconnection of the standing potential by relay or similar means, triggered by the discharge in the last gap or by a local quenching pulse similarly triggered. This would do away with the need for condenser 23.

A tube having the memory effect could be used in either application, in which case, in the Figure 1 arrangement, the stabilising circuit 21, 22 would be unnecessary, whereas in the Fig. 2 arrangement, the need for specific extinguishing means, at the end of a cycle, would also be unnecessary.

It has already been pointed out, however, that, if there is a break between the end of the signal

pulses and the application of the master pulses which exceeds the deionising time of the tube, measures must be taken to prolong the discharge in the gap fired by the last signal pulse so that the master pulse fires the next gap thereafter and does not start from the beginning of the tube.

In the circuit of Fig. 2, it would also be possible to resort to the arrangement described in my application, Serial Number 777,815, filed October 3, 1947, whereby, at the end of a firing cycle, one or more pulses are prevented from causing discharges in the tube to allow extra time for deionising where pulse rates are used which do not allow time enough for deionising between consecutive pulses.

In describing the embodiments shown in Figs. 1 and 2, the possibility of applying an initial train of signal pulses greater in number than the firing cycle of the tube, has not been mentioned, but it will be obvious that this might be done and it is within the scope of the invention.

In such a case, the tube would complete a number of operative cycles equal to the number of complete multiples of the pulses in the cycle, contained in the number of applied signal pulses and thereafter would fire a number of gaps equal to the balance of the signal pulses.

This might, for instance, be used to record the units digit of a multi-digit number, the other digits, derived either from a circuit connected to the last gap of the tube, or in some other way, being recorded elsewhere.

What is claimed is:

1. An electronic device which comprises a cold cathode gaseous discharge tube having a number of gaps arranged in sequence to fire in succession in a predetermined order on the application, to the said gaps, of consecutive pulses of electrical energy due to the influence of a fired gap on the potential required to fire an adjacent unfired gap, means for applying in turn to the said tube a first group of pulses, means under control of said first means and responsive to the end of the last pulse of said first group for applying to the said tube a second group of pulses, and means also under control of said first means for giving a signal dependent on the firing of a predetermined gap during the application of the second group of pulses.

2. An electronic device, as claimed in claim 1, in which the tube is arranged to respond to repeated cycles of pulses, each having pulses at least equal in number to the number of the said gaps, and in which the second group of pulses contain a number of such cycles, the said signal being repeated each time the said predetermined gap is fired and defining a phase position in each cycle.

3. An electronic device, as claimed in claim 2, comprising means for producing a repetitive connecting signal synchronized with the first pulse in each cycle of said second group, the means for applying the second group of pulses also being under control of said connecting signal.

4. An electronic device, as claimed in claim 1,

comprising means for modulating the signal dependent on the firing of the predetermined gap.

5. A device, as claimed in claim 1, in which the tube is arranged to respond to repeated cycles of pulses, each having pulses at least equal in number to the number of the gaps, and in which the second group of pulses contains a number of such cycles, the said cycles being repeated each time the said predetermined gap is fired and defining a phase position in each cycle, and further comprising means for producing a repetitive connecting signal synchronized with the first pulse in each cycle of said group, and means for applying the second group of pulses comprising an electronic circuit having two stable conditions in the first of which pulses of the second group are withheld from the said gaps and in the second of which pulses of the said second group are applied to the said gaps, and means for causing said connecting signal to shift said circuit from said first condition to said second condition.

6. An electronic device comprising a cold cathode gaseous discharge tube having a gap adapted to discharge during the application thereto of pulses of electrical energy, means for applying pulses to said gap, means connected to said gap for producing a signal when said gap fires, and means for modulating the pulses applied to said gap so as to vary the time of firing and thus modulate the signal with respect to time.

7. An electronic device, as claimed in claim 6, in which means is provided for extinguishing the said gap between successive pulses of a sequence of pulses applied thereto and in which the signals, dependent on the repeated firing of the said gap during the application of the said pulses, are successively modulated by the said modulating means.

8. An electronic device, as claimed in claim 7, in which the modulating means includes means responsive to audio frequency current or voltage.

9. An electronic device, as claimed in claim 6, in which the said gap is one of several gaps in a cold cathode gaseous discharge tube such gaps being adapted to fire in succession in a predetermined order on the application of consecutive pulses of electrical energy due to the influence of a fired gap on the potential required to fire an adjacent unfired gap, and in which means is provided for extinguishing the said gap between successive pulses of a sequence of pulses applied thereto and in which the signals, dependent on the repeated firing of the said gap on or during the application of the said pulses, are successively modulated by said modulating means.

ALEC HARLEY REEVES

It is hereby certified that errors appear in the printed specification of the above numbered patent requiring correction as follows:

Column 1, line 36, strike out the words and comma "now abandoned,", and insert the same in line 38, same column, after "July 25, 1947,"; and that the said Letters Patent should be read with these corrections therein that the same may conform to the record of the case in the Patent Office.

Signed and sealed this 22nd day of August, A. D. 1950.
